UNITED STATES PATENT OFFICE.

WILLIAM F. LOUDON, OF STONINGTON, CONNECTICUT.

LAMP.

SPECIFICATION forming part of Letters Patent No. 738,689, dated September 8, 1903.

Application filed March 15, 1902. Serial No. 98,327. (No model.)

To all whom it may concern:

Be it known that I, WILLIAM F. LOUDON, a citizen of the United States, residing at Stonington, in the county of New London and State of Connecticut, have invented certain new and useful Improvements in Lamps; and I do hereby declare the following to be a full, clear, and exact description of the invention, such as will enable others skilled in the art to which it appertains to make and use the same.

The present invention relates to improvements in lamps, and more particularly to certain improvements in that type of lamp in which the kerosene is formed into a vapor or gas previous to being ignited and which are generally known as "hydrocarbon-burners."

The object of the present invention is to so construct the lamp that the globe thereof may be readily placed in position or removed therefrom and be held firmly in position and prevented from rattling while the lamp is in use; and a further object of the invention is to provide means for regulating the admission of air to the dome of the lamp.

To the above ends the present invention consists of the devices and combinations of devices which will be hereinafter described and claimed.

The present invention is illustrated in the accompanying drawings, in which—

Figure 1 shows in front elevation a lamp embodying my improvements. Fig. 2 shows in side elevation the upper portion of the lamp, illustrating in dotted lines the operation of the dome.

Similar reference characters will be employed throughout the specification and drawings to designate corresponding parts.

The lamp consists of a globe or receptacle *a*, which receives the kerosene or other oil, provided with a valve *b*, by means of which a pump may be attached to place the oil in the tank *a* under pressure sufficient to force it up the pipe *c* to the vaporizing devices contained in the dome *d*, from which it is led down the pipe *e* in the form of a gas or vapor to the burner *f*, all as will be clearly understood by those persons skilled in this art.

The device as so far described is of the usual and ordinary construction and in and of itself forms no part of the present invention.

A glass globe *g* surrounds the burner and the flame and at its lower edge rests upon a circular table *h*, which is provided with a groove (not shown) in which the lower edge of the globe *g* fits. The upper part of the globe *g* is of a diameter substantially the same as the diameter of the lower part of the dome, and, as shown clearly in dotted lines, encircles and receives the lower part of the dome, the arrangement being such that when the parts are adjusted as shown in Fig. 1 of the drawings the globe *g* will be firmly held in position on the table *h*.

Surrounding the dome *d* is a metallic cap or shade *i*, having an opening *j*, which is substantially the diameter of the dome *d* and gradually flaring outwardly toward its base. This cap *i* is arranged to slide up and down along the dome *d*, its normal position when the globe *g* is in place being shown in full lines in Fig. 1 and resting upon the upper edge of the globe *g*. When it is desired to remove the globe *g*, the cap *i* is moved upward to the position shown in dotted lines, and I have provided suitable means—such as a spring-latch *k*, having a hooked end arranged to take over a bead or rib *l*—at the upper edge of the dome, whereby the cap will be held in dotted-line position while the globe *g* is being removed or replaced.

For the purpose of facilitating the removal of the globe *g* I have pivotally mounted the dome *d* upon the inturned upper ends of the pipes *e* and *c*, so that said dome may be tilted, as shown in dotted lines, Fig. 2, and before the globe *g* can be removed the dome *d* must be moved to the position shown in dotted lines. In order to maintain the dome *d* in the full-line position shown in Fig. 2 and to prevent its accidental tipping, I have provided the same with a latch *m*, having a hooked end *n* arranged to engage a curved or yoke-shaped brace *o*, which is connected at its ends to the pipes *e* and *c* and extends in a curved line around the rear of the dome *d*. This brace *o* serves the double purpose of coöperating with the latch *m* and strengthening and supporting the pipes *e* and *c*. When it is desired to remove the globe *g*, the latch *m* will be released from its engagement with the yoke *r* and the globe *g* raised, carrying with it the cap *i* to the position shown

in dotted lines, Fig. 1, whereupon the dome *d* will be tilted, as shown in Fig. 2, permitting the ready removal of the globe *g*.

The dome *d* is provided with an opening *p*, which may be closed by a suitable sliding plate (not shown) whereby to permit the entrance of a match or other light to ignite the vapor forming the light.

It is desirable in lamps of this kind to regulate the admission of air to the vaporizing apparatus, the air entering the dome *d* at an opening surrounded by a cup-shaped or annular disk *g*, and I have provided a cap or cover *r*, having a threaded opening arranged to engage a short threaded section *s* on the upper end of the pipe *e*, the arrangement being such that the cap *r* may be adjusted to and from the cup-shaped disk *g*. By this means I control the flow of air to the vaporizing apparatus.

The operation of my invention has been sufficiently set forth in connection with the foregoing description of its form and arrangement, and a further description thereof is deemed unnecessary.

Having described my invention, I claim as new and desire to protect by Letters Patent of the United States—

1. A lamp provided with a table, a globe resting on said table, a dome pivoted to upright standards and engaging the upper end

of said globe, a transverse member connecting said upright standards, and a latch secured to the dome and adapted to engage said transverse member, substantially as described. 35

2. A lamp provided with a table, a globe resting upon said table, a dome engaging the upper end of the globe, an elongated rib upon said dome, a shade slidably fitted upon said dome and normally resting upon the globe, and a latch mounted upon said shade and adapted to engage the rib for holding the shade raised, substantially as described. 40

3. A lamp provided with a table, a globe resting on said table, a dome pivoted to upright standards and engaging the upper end of said globe, a transverse member connecting said upright standards, a latch secured to the dome and adapted to engage said transverse member, a shade slidably fitted upon said dome and complementary latch elements secured to said dome and to said shade whereby the shade may be held in an elevated position, substantially as described. 45 50

In testimony whereof I affix my signature in presence of two witnesses.

WILLIAM F. LOUDON.
